[57] CLAIM

The ornamental design for a coverall, as shown and described.

DESCRIPTION

FIG. 1 is a front elevational view of a coverall showing our new design, the broken lines representing conventional stitching;

FIG. 2 is a left side elevational view thereof;

FIG. 3 is a right side elevational view thereof;

FIG. 4 is a top plan view thereof;

FIG. 5 is a bottom plan view thereof; and

FIG. 6 is a rear elevational view thereof; the broken lines representing conventional stitching.

*Fig. 4**Fig. 1**Fig. 2**Fig. 3**Fig. 5*
